(21) Appl. No.: **29/179,129**

(57) CLAIM

(22) Filed: **Apr. 4, 2003**

The ornamental design for a developer supplying device for image forming apparatus, as shown and described.

(30) **Foreign Application Priority Data**

DESCRIPTION

Oct. 4, 2002 (JP) 2002-027234

(51) LOC (7) Cl. **16-03**

FIG. 1 is a front perspective view of a developer supplying device for image forming apparatus;

(52) U.S. Cl. **D18/40**

FIG. 2 is a rear view thereof;

(58) Field of Search D18/12, 40, 43,

FIG. 3 is a front view thereof;

D18/56; D14/471, 481, 483; 222/DIG. 1;

FIG. 4 is a right side view thereof;

399/24-31, 110-125, 252-263, 130, 222-224

FIG. 5 is a left side view thereof;

(56) **References Cited**

FIG. 6 is a top view thereof; and,

U.S. PATENT DOCUMENTS

FIG. 7 is a bottom view thereof.

D410,947 S * 6/1999 Schwamkrug D18/43
D442,216 S * 5/2001 Kimura et al. D18/43

The broken lines shown in FIGS. 1, 3, 4, 5, 6, and 7 are for illustrative purposes only and form no part of the claimed design.
